CLAIM

The ornamental design for a portable fence energizer, as shown and described.

DESCRIPTION

FIG. 1 is a perspective view of a portable fence energizer according to the present invention;

FIG. 2 is front view of the portable fence energizer of FIG. 1;

FIG. 3 is a back view of the portable fence energizer of FIG. 1;

FIG. 4 is a top of the portable fence energizer of FIG. 1;

FIG. 5 is a bottom view of the portable fence energizer of FIG. 1;

FIG. 6 is a left side view of the portable fence energizer of FIG. 1; and,

FIG. 7 is a right side view of the portable fence energizer of FIG. 1.

The broken lines shown in the drawings are for the purpose of illustrating portions of the portable fence energizer that form no part of the claimed design.

1 Claim, 7 Drawing Sheets
